ROLLIN ABELL, OF MILTON, MASSACHUSETTS

ENGINE STARTER

Application filed April 6, 1925. Serial No. 20,960.

This invention relates to starters for internal combustion engines, and especially to the type that comprises an axially movable transmission unit having a starting pinion for engaging and disengaging a gear of the engine.

One difficulty with commercial engine-starters of this type is that when the engine backfires it bends or breaks the starting shaft or some other part of the mechanism, or dislodges the starting motor from its anchorage. To avoid the more damaging consequences some starters include a spring to transmit rotation to the starting pinion, but when such a spring is subjected to the stress of a backfire it breaks. Thus, while the cost of a new spring is not so serious as the damage that would otherwise occur, the inconvenience of losing temporarily the use of the starter, and the labor cost of installing a new spring make the total consequence of spring breakage a matter of considerable moment.

Therefore, one of the objects of the present invention is to provide an improved engine-starter that will automatically relieve itself from the damaging stresses of a backfire or other overload and still be in condition to operate. A feature by which this is obtained consists in a novel form of mechanism for shifting the pinion of the transmission unit into gear and applying the starting torque thereto. Unlike most forms of mechanism for this purpose, this mechanism is formed to run out of its driving connection while the starting pinion remains in gear under conditions of abnormally great torque, as when the engine backfires or fails to turn while the starting motor is running.

To utilize the aforesaid mechanism to effect a start under normal conditions the invention consists further in providing a spring to balance the torque and any load within a safe limit. Thus, by combining the balancing spring with driving mechanism of the running-out type, the invention eliminates all shocks and impacts with respect to both axial movement and torque, in addition to providing an overrunning driving connection between the starting motor and the starting pinion to guard against damage to the starting mechanism. Furthermore, the

running-out mechanism is organized to restore itself automatically to operative condition after relieving itself from abnormally great torque.

Other features of the invention are hereinafter described and claimed and are illustrated by the drawings.

Figure 1 is an elevation of a starting mechanism embodying a preferred form of the invention.

Fig. 2 is a longitudinal section thereof showing the parts in their initial or out-of-gear position.

Fig. 3 is a longitudinal section showing the transmission unit in gear and as having passed beyond its normal operating position, and the operating mechanism as having run out of its operating connection to relieve an abnormal torque.

Fig. 4 is an elevation of the sleeve that relieves the starting shaft of lateral stresses.

Fig. 5 is a development, on a smaller scale, of a preferred type of cam member for shifting the starting pinion axially.

The journal portion of an electric motor casing is indicated at 10, and the armature shaft at 11. An outboard extension 12 of this shaft (hereinafter termed the "starting shaft") carries the starting mechanism which is arranged close to a spur gear 13 of the internal combustion engine. The gear 13 is shown as carried by the fly-wheel of the engine, a portion of which is indicated at 14. A bearing sleeve 15 is slipped on the starting shaft and fits into the journal portion 10 to relieve the outboard extension from lateral stress. An internal shoulder 16 of the sleeve abuts against a shoulder 17 on the shaft to maintain the outboard end of the sleeve at the desired distance from the motor casing.

An axially movable transmission unit is arranged on the shaft extension 12. As shown, this unit comprises a starting pinion 18, a barrel-shaped cam portion 19 and an internal bearing portion 20 formed to bear on the shaft extension. A counterbore 21 contains a compression spring 22 and the outboard end of the sleeve 15, the transmission unit thus having a direct bearing on the sleeve in addition to its bearing on the shaft

extension. The sleeve preferably extends across the face of the gear 13 to afford ample bearing surface to the transmission unit and to sustain the lateral stresses of reaction between the pinion and the gear so that these stresses will not be borne by the shaft.

An operating device is secured to the outboard end of the shaft by a key 23 and a set-screw 24. This device, as shown, consists of 10 a sleeve having preferably two diametrically opposite stud portions or lugs 25 projecting radially to cooperate with reactive cam slots 26 formed in the cam portion 19. When the stud-portions 25 are in the slots as shown 15 by Figs. 1 and 2 the operating device is nested in the barrel-shaped portion 19, but the outboard ends of the slots 26 are open to permit the studs to run out in operation under abnormal conditions so that the operating unit may overrun the transmission 20 unit while the pinion 18 is in gear. See Fig. 3. The end face 27 of the barrel-shaped part 19 is at right angles to the axis of rotation and is annular, except that it is intersected 25 by the cam slots 26. Thus, the entrance of the studs 25 into the slots is limited by circumferential portions of the barrel-shaped part 19 which serve as guards to maintain the pinion in mesh with the gear 13 in case of 30 overload or backfire until both the operating unit and the transmission unit have come to rest. When the device encounters an overload or a backfire the driving portions of the two units wedge themselves apart, the studs 35 run out of the slots 26 and run on the end face 27, and the transmission unit is thereafter maintained by the latter in an axially advanced position until the parts come to rest with the studs in the open ends of the 40 cam slots, whereupon the reaction of the spring 22 restores the parts to their initial nested relation shown in Figure 1. The cam slots are preferably curved to have graduated steepness or pitch, and the steepest portions 45 are at the outboard end, that is, at the end toward which the stud portions move from their initial positions at the inner ends of the slots.

The spring 22 is preferably stiff and 50 shorter than the space provided for it in the counterbore 21, to permit the pinion to move into gear without opposition and then to resist further axial movement with strong and rapidly increasing force. The pressure is 55 applied to the spring by the bearing portion 20 and is sustained by the sleeve 15 and the starting shaft by reason of the shoulders 16 and 17. This does not produce end-thrust of the shaft because the counteractive pressure in the opposite direction is also sustained by the shaft through the operating 60 connections.

Assuming that the transmission unit is in its initial position, as shown by Fig. 1, the 65 pinion 18 being then out of gear, and that

current is applied to energize the starting motor, the shaft 11 will rotate in the direction indicated by the arrow on Fig. 2. Before the operating connections can fully overcome the inertia of the transmission unit the studs 25 will move the latter axially to mesh the pinion 18 with the gear 13. This will occur before any compression is developed in the spring 22, but when the pinion reaches the normal operating position indicated by broken lines in Fig. 2 but subject to slight variations according to load conditions the spring will have been compressed enough to develop a starting torque sufficient for normal loads. Under these conditions the spring will balance the operating torque and the load, since the studs will still be in the cam slots but will be acting on the steeper parts thereof, and if the engine responds and operates on its own power it will turn the pinion faster than the shaft 11 and cause a reaction of the cams and studs to shift the transmission unit to its initial position.

On the other hand, if the engine does not respond, or if it backfires, the studs and cams will shift the transmission unit farther to the left (see Fig. 3), whereupon the studs will run out of the open ends of the cam slots and run around on the outboard end of the cam portion 19 without producing any further axial movement. Thus, the effective connection of the operating members will be automatically ruptured to release the operating unit from the engine without disengaging the pinion 18 from the gear 13.

This abnormal operation does not fully compress the spring or cause the transmission unit to strike any positive abutment, since the construction provides sufficient margins of clearance to avoid such undesirable results. The studs 25 will click over the open ends of the cams until the starting shaft stops turning, but will eventually come to rest in the slots and thus automatically restore the parts to operative relation. It is to be observed that the transmission unit does not include any slipping parts, disconectible clutch or driving spring between the pinion and the operating element 19, but that the running-out feature of the operating elements affords all that is necessary to relieve the torque under abnormal conditions.

What I claim is:

1. An engine-starter comprising a starting shaft, an axially movable transmission unit provided with a starting pinion arranged on said shaft, an operating member fastened to said shaft, said unit and said member having one an open-ended reactive cam slot and the other a lug arranged to form an operating connection to shift said unit axially in opposite directions, and a spring arranged to act on said unit to develop the starting torque for normal loads, said lug and said member being formed and

- arranged to run out of their operating connection in case of an overload or a backfire and to maintain the transmission unit advanced axially until the operating member comes to rest. 5
2. An engine-starter comprising an axially movable starting pinion, a rotary operating member, transmission means with which said operating member co-operates to shift said pinion axially and drive it rotatively, said means and said member having initially connected operating portions including an open-ended cam slot and a lug, and a spring arranged to oppose such axial shifting and to develop the starting torque for normal loads while said slot and said lug are in driving relation, said operating portions being arranged to run out of their driving relation in case of overload and to maintain the pinion in an axially advanced position until the operating member comes to rest. 10
3. An engine-starter comprising an axially movable starting pinion, rotary means formed and arranged to shift said pinion axially and drive it rotatively, and a spring arranged to oppose axial movement of said pinion to its operative position, said rotary means including relatively rotatable members of which one is formed with a cam slot of increasing pitch open at its steeper end and the other of which has a lug initially in said slot, said members being formed and arranged to force said lug out of said open end of said slot in case of overload and to maintain the pinion axially advanced until relative rotation of said members ceases. 15
4. An engine-starter comprising an axially movable transmission unit including a starting pinion, a rotary operating member, said member and said unit having one a cam slot open at one end and the other a cam-engaging stud arranged to shift said unit axially and drive it rotatively, a spring arranged to resist axial movement of said unit to balance the torque and normal loads, the range of axial movement afforded by said spring being greater than that produced by said cam and stud and the latter being formed and arranged to run out of said open end of said cam slot in case of overload, and means arranged to maintain said transmission unit in an axially advanced position after such running out of said stud until said operating member and said transmission unit both come to rest. 20
5. An engine-starter comprising a rotary operating unit, a rotary and axially movable transmission unit provided with a starting pinion, and a spring arranged to balance the starting torque and normal loads by opposing axial movement of said transmission unit, one of said units having a barrel-shaped part provided with a cam slot of graduated pitch open at one end and closed at the other 25
- end and the other one of said units having a stud arranged to cooperate with said slot to shift and drive said transmission unit, the pitch of said cam slot being relatively steep adjacent to said open end but adapted to cause said stud to run out and run on one end of said barrel-shaped part in case of overload, said barrel-shaped part being formed to maintain the transmission unit in an axially advanced position until said operating units comes to rest. 30
6. An engine-starter comprising a rotary operating unit, a rotary and axially movable transmission unit provided with a starting pinion, and a spring arranged to balance the axial effort of said transmission unit against normal loads, said units having cooperative driving parts normally maintained in nested relation by said spring, one of said parts having a cam slot open at one end and the other one of said parts having a lug initially in said slot but arranged to run out of the open end of said slot in case of overload and to maintain said transmission unit in an axially advanced position until said operating unit comes to rest. 35
7. An engine-starter comprising a starting shaft, an operating member fastened thereto, an axially movable transmission unit arranged on said shaft and including a starting pinion, said operating member and said unit having cooperative portions initially nested one in the other, the outer one of said portions having a cam slot and the inner one having a lug to cooperate therewith to shift the transmission unit axially and drive it rotatively, and a spring arranged to act on said transmission unit to balance the torque and normal loads, said nested portions being formed to run out of nested relation under abnormal loads and thereby rupture the driving connection to relieve the torque. 40
8. An engine-starter comprising a rotary operating unit, an axially movable transmission unit provided with a starting pinion, a spring arranged to balance the starting torque and normal loads by opposing axial movement of said transmission unit, said units having initially interengaged driving portions formed to wedge themselves apart with relative axial movement in case of overload, and means arranged to maintain said transmission unit in an axially advanced position so that said operating unit may overrun said transmission unit until the operating unit comes to rest. 45
9. An engine-starter comprising a rotary operating unit, a rotary and axially movable transmission unit provided with a starting pinion, and a spring arranged to balance the axial effort of said transmission unit against normal loads, one of said units having a plurality of radial studs and the other having a barrel-shaped part provided with a substantially annular end face at right angles to the 50

axis of rotation and with cam slots intersecting said end face to receive said studs and to cause them to run out and run on said end face in case of overload, said end face being formed to maintain said transmission unit in an axially advanced position after such running out until said operating unit comes to rest.

- 5 10. An engine-starter comprising a rotary operating unit, a rotary and axially movable transmission unit provided with a starting pinion, one of said units having a barrel-shaped part formed with a cam slot that intersects one end thereof and provides a guard to restrict the entrance to said cam slot, the other one of said units having a stud formed and arranged to cooperate with said cam slot to shift said transmission unit axially and drive it, and a spring arranged to act on said transmission unit to balance the starting effort against normal loads, said stud being arranged to run out of said slot in case of overload and to run on said end of said barrel-shaped part, and said guard being formed to maintain said transmission unit in an axially advanced position until said operating unit comes to rest.
- 15 20 25

11. A combination comprising an engine gear, a starting pinion movable axially into and out of mesh with said gear, two coaxial and relatively rotatable elements having one a cam surface and the other a lug formed and arranged to coact one against the other to shift said pinion axially into gear and drive it, a spring arranged to balance the torque and normal loads by opposing such shifting of said pinion, said two elements being formed one to overrun the other when an overload or backfire is encountered, and means arranged to maintain said pinion thereafter in mesh with said gear until both of said elements come to rest, said means being intersected by an opening through which the lug may pass to permit said spring to demesh said pinion when said elements come to rest.

In testimony whereof I have affixed my signature this 26th day of March, 1925.

ROLLIN ABELL.
